(57) **CLAIM**

The ornamental design for a luminaire with horizontal light fixtures, as shown and described.

DESCRIPTION

FIG. 1 is a perspective view of a luminaire with horizontal light fixtures, showing my new design;

FIG. 2 is a front-side elevation view thereof;

FIG. 3 is a rear-side elevation view thereof;

FIG. 4 is a bottom plan view thereof;

FIG. 5 is a top plan view thereof;

FIG. 6 is a left-side elevation view thereof; and,

FIG. 7 is a right-side elevation view thereof.

The broken lines shown represent unclaimed subject matter and form no part of the claimed design.
